(57) **CLAIM**

The ornamental design for a scribe, as shown and described.

DESCRIPTION

FIG. 1 is a perspective view from above of my new design for a scribe.

FIG. 2 is an top plan view of the scribe shown in FIG. 1.

FIG. 3 is an elevational view of the front of the scribe shown in FIG. 1.

FIG. 4 is an elevational view of the back of the scribe shown in FIG. 1.

FIG. 5 is a bottom plan view of the scribe shown FIG. 1.

FIG. 6 is an end elevational view from the right side of the scribe shown in FIG. 1; and,

FIG. 7 is an end elevational view from the left side of the scribe shown in FIG. 1.

The broken lines depicting a pencil in FIG. 1 are included for the purpose of illustrating a feature that forms no part of the claimed design.

1 Claim, 4 Drawing Sheets

FIG. 6

FIG. 7
